[57] CLAIM

The ornamental design for keyboard, as shown and described.

DESCRIPTION

FIG. 1 is the perspective view of a keyboard showing my new design;

FIG. 2 is the front elevational view thereof;

FIG. 3 is the rear elevational view thereof;

FIG. 4 is the left side elevational view thereof;

FIG. 5 is the right side elevational view thereof;

FIG. 6 is the top plan view thereof; and,

FIG. 7 is the bottom plan view thereof.

The zigzag pattern shown on the right side of the keyboard underneath the keys in FIGS. 1 and 6 represents a conventional material.
